(57) **CLAIM**

The ornamental design for an air cleaning machine, as shown and described.

DESCRIPTION

FIG. 1 is a front view of an air cleaning machine in accordance with an embodiment of my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view of the front, top, and right sides thereof; and,

FIG. 8 is a perspective view of the front, top, and left sides thereof.

The broken lines shown in the figures depict portions of the air cleaning machine that form no part of the claimed design.
